UNITED STATES PATENT OFFICE.

REA P. WRIGHT, OF WASHINGTON, DISTRICT OF COLUMBIA, ASSIGNOR TO THE AMERICAN WINGER COMPANY, OF WOONSOCKET, RHODE ISLAND, A CORPORATION OF RHODE ISLAND.

PRESSURE-ROLL RELEASE FOR CLOTHES-WRINGERS.

1,219,523.

Specification of Letters Patent. Patented Mar. 20, 1917.

Application filed July 26, 1916. Serial No. 111,406.

To all whom it may concern:

Be it known that I, REA P. WRIGHT, a citizen of the United States, residing at Washington, in the District of Columbia, have invented certain new and useful Improvements in Pressure-Roll Releases for Clothes-Wringers, of which the following is a specification, reference being had thereto in the accompanying drawing.

- 10 This invention relates to certain new and useful improvements in pressure roll releases for clothes wringers, the object being to provide a releasing device for the pressure rolls of the wringer in the form of a resilient member having its ends interlocked in keepers carried by the side bar of the wringer in such a manner that the same can be instantaneously released in order to allow the pressure rolls to move vertically.
- 15 Another object of my invention is to provide a pressure release which is exceedingly simple and cheap in construction and one which can be readily installed on the ordinary form of clothes wringer now in use.
- 20 Other and further objects and advantages of the invention will be hereinafter set forth and the novel features thereof defined by the appended claims.

In the accompanying drawings,

30 Figure 1 is a front view of a clothes wringer partly in section showing the application of my improved construction of pressure roll release thereto;

Fig. 2 is a section taken on the line 2—2 of Fig. 1;

35 Fig. 3 is a detail perspective view of a keeper secured to the inner face of the side bars and a portion of the resilient member;

Fig. 4 is a detail section partly in elevation showing another form of keeper and resilient member, and

Fig. 5 is a perspective view of the keeper and a portion of the resilient member as shown in Fig. 4.

45 Like numerals of reference refer to like parts in the several figures of the drawing.

In the drawing 1 indicates a wringer frame which is composed of the usual slotted side bars connected together adjacent their lower ends by connecting members; and 2 and 3 the pressure rolls which are carried by shafts arranged in suitable bearings slidably mounted in the slotted side bars of the wringer frame. The upper bearings are

preferably provided with spring supports 4 55 carrying pressure springs 5 on which is mounted a pressure bar 6, the above description being given so that the operation of my improved construction of releasing device when attached to this form of wringer 60 can be clearly understood.

Slidably mounted within the upper portions of the slotted side bars of the wringer frame, is a top bar 7 having pressure screws 8 mounted in suitable threaded boxes carried thereby, said pressure screws coöperating with the pressure bars 6 so as to adjust the pressure on the pressure rolls through the medium of the springs.

In constructing my improved release for 70 wringers, I employ a resilient member 9 preferably formed of spring wire having a central bowed portion 10 and horizontally disposed ends 11 which are reduced as shown at 12. In applying the resilient releasing 75 member to a clothes wringer, I provide the top bar 7 with a vertically disposed slot 13 in which the bowed portion 10 of the resilient member is freely mounted; the horizontally disposed end portions 11 being 80 mounted in screw eyes 14 secured to the lower face of the bar as clearly shown in Fig. 1, forming guides for the end portions of the resilient member in order to allow the resilient member to expand and contract as 85 pressure is placed upon the same and released therefrom, for the purpose herein-after fully described.

Secured to the inner faces of the side bars of the wringer frame are keepers 15 which 90 are in the form of plates having substantially key-hole shaped slots, the enlarged portions thereof forming sockets for the extreme end portions of the resilient member 9 so as to hold the top bar in a predetermined 95 position within the wringer frame to enable the pressure screws 8 to be adjusted to regulate the pressure on the pressure rolls.

When the pressure releasing device is in the position as shown in Fig. 1, the bowed 100 portion 10 of the resilient member is in a plane above the top bar in such a position that the same can be readily struck by the operator of the wringer when it is desired to release the pressure on the pressure rolls 105 in case of an accident. As the resilient member 9 is removed downwardly by the impact of the blow from the operator of

the machine, the ends thereof are moved outwardly by the elongation of the spring, the horizontally disposed portions sliding in the screw eyes 14 until the reduced portions 12 are in alinement with the reduced portions of the key-hole shaped slots in the keepers 15 which allows the top bar to move upwardly.

In the form shown in Figs. 4 and 5, I provide keepers 16 which are secured on the outer faces of the side bars of the wringer frame and are provided with key-hole openings to allow the resilient member to move vertically therein when the reduced portion is brought into alinement with the vertically disposed portion thereof, but limits the upward movement thereof so as to prevent the top bar from becoming detached from the wringer frame. In this form the resilient member 17 is also mounted in screw eyes 18 secured to the under side of the top bar, and the ends thereof are provided with offset portions 19 extending around the pressure screws 8, the extreme end portions being provided with the reduced portions which when brought into alinement with the reduced portions of the key-hole shaped slots of the keepers allow the top bar to move vertically within the wringer frame to release the pressure on the pressure rolls. In this form the operation of the resilient member is identical with the operation of the preferred form shown, as when the resilient member is struck a blow, the ends thereof are forced outwardly so as to bring the reduced portions into such position within the keepers that the top bar is released.

By constructing the resilient member with an offset portion at each end extending around the pressure screws, I am able to place the keepers on the outer faces of the side bars, as in some constructions of clothes wringers this might be used with advantage over the keepers arranged on the inner face of the side bars of the wringer frame.

From the foregoing description it will be seen that I have provided a pressure release for clothes wringers which is composed of a resilient member formed of a single piece of wire mounted in a pair of screw eyes and coöperating with a pair of keepers in such a manner that the top bar of the wringer frame is held in position within the wringer frame so that the same can be instantaneously released, as by forming the resilient member of the central bowed portion extending through the top bar above the upper surface thereon, I eliminate operating members of any kind, and I am able to release the pressure on the rolls quickly.

I claim:

1. A clothes wringer, comprising a frame having pressure rolls and pressure means

for said rolls mounted therein, a movably mounted top bar arranged in said frame, keepers carried by the side bars of said frame, and a resilient member slidably mounted on the under face of said top bar having a central bowed portion extending upwardly into a plane above the top of said bar.

2. A clothes wringer, comprising a frame having pressure rolls and pressure means for said rolls mounted therein, a top bar having pressure screws for adjusting said pressure means, guide members secured to the under face of said top bar, a resilient member slidably mounted in said top bar having horizontally disposed portions mounted in the guide members thereof, keepers carried by the side bars provided with key-hole shaped slots, said resilient members having reduced portions coöperating with said slots for releasing said top bar.

3. A clothes wringer, comprising a frame having pressure rolls and pressure means for said rolls mounted therein, a movably mounted top bar carrying pressure screws for adjusting said pressure means, said top bar having a vertically disposed slot, a resilient member having a bowed portion arranged within said slot and extending upwardly above the upper face thereof, guide members carried by the under face of said top bar to receive the end portions of said resilient members, and keepers carried by said side bars adapted to receive the end portions of said resilient member.

4. A clothes wringer, comprising a frame having pressure rolls and pressure means for said rolls mounted therein, a movably mounted top bar carrying pressure screws for adjusting said means, keepers carried by the side bars of said frame, and a bowed resilient member slidably mounted within said top bar having reduced end portions coöperating with said keepers for releasing said top bar.

5. A clothes wringer, comprising a frame having pressure rolls and pressure means for said rolls mounted therein, a movably mounted top bar carrying pressure screws for adjusting said pressure means, said top bar having a vertically disposed slot, a resilient member formed of a single piece of wire having a bowed portion extending through said slot and provided with horizontally disposed ends slidably mounted in guides carried by the under side of said top bar, and keepers carried by the side bars of said frame for holding said top bar in predetermined position within said frame.

6. A clothes wringer, comprising a frame having pressure rolls and pressure means for said rolls mounted therein, a movably mounted top bar arranged within said frame having a vertically disposed slot,

guide members secured to the under face of said top bar, keepers carried by the side bars of said frame, and a resilient member having a central bowed portion extending 5 through the slot of the top bar and provided with horizontally disposed end portions slidably mounted within said guide members and coöperating with said keepers for holding said top bar in predetermined position 10 within said frame.

7. A clothes wringer, comprising a frame having pressure rolls and pressure means for said rolls mounted therein, a top bar movably mounted within said frame having 15 pressure screws for adjusting said pressure means, said top bar being provided with an opening, keepers secured to the side bars of said frame provided with key-hole shaped openings, and a resilient member having a 20 central bowed portion extending through the opening of said top bar and having horizontally disposed end portions provided with reduced portions coöperating with said key-hole shaped slots for releasing said top 25 bar to reduce the pressure on said pressure rolls.

8. A clothes wringer, comprising a frame having pressure rolls and pressure means for said rolls mounted therein, a movably 30 mounted top bar arranged within said frame having pressure screws for adjusting said pressure means, keepers secured to the side bars of said frame provided with key-hole shaped openings, said top bar being 35 provided with a vertically disposed slot, guide members secured to the under face of said top bar, a resilient expandible member slidably mounted within said guide members, having its end portions coöperating 40 with said key-hole shaped openings of the keepers for holding and releasing said top bar, said resilient member having a cen-

trally disposed bowed portion extending through the opening of said top bar.

9. A clothes wringer, comprising a frame 45 having pressure rolls and pressure means for said rolls mounted therein, a movably mounted top bar carrying pressure screws for adjusting said pressure means, keepers provided with key-hole shaped openings carried by the side bars of said frame, guide members secured to the under side of said top bar, said top bar being provided with a vertically disposed opening, a resilient expandible member having a central 50 bowed portion disposed within said slot, and provided with horizontally disposed end portions extending through said guide members, said horizontally disposed end portions being provided with reduced portions 55 coöperating with said key-hole shaped openings of the keepers for releasing said top bar to reduce the pressure on said pressure rolls.

10. A clothes wringer, comprising a frame 65 having pressure rolls and pressure means for said rolls mounted therein, a top bar carrying pressure screws for adjusting said pressure means, said top bar having a resilient member 70 slidably mounted on the under face thereof, said resilient member having a bowed portion extending upwardly into a plane above the top of said top bar, keepers carried by the side bars of said frame provided with key-hole shaped openings to 75 receive the extreme end portions of said resilient member for holding said top bar in predetermined position within said frame, said resilient member having reduced portions 80 coöperating with the openings of the keepers for releasing said top bar.

In testimony whereof I hereunto affix my signature.

REA P. WRIGHT.
